[57] CLAIM

The ornamental design for shoe outsole, as shown and described.

DESCRIPTION

FIG. 1 is a bottom plan view of a left shoe outsole showing our new design, the right shoe outsole being a mirror image thereof, the broken lines showing a shoe midsole are for illustrative purposes only and form no part of the claimed design;

FIG. 2 is a left side elevational view thereof, the broken lines shown showing a shoe upper and /or shoe midsole are for illustrative purposes only and form no part of the claimed design;

FIG. 3 is a left side elevational view thereof;

FIG. 4 is a front elevational view thereof;

FIG. 5 is a rear elevational view thereof;

FIG. 6 is a top plan view thereof, the broken lines shown showing a sole and/or midsole are for illustrative purposes only and form no part of the claimed design; and,

FIG. 7 is a cross-sectional view thereof taken about lines 7—7 in FIG. 1 showing the cross-section of an exemplary pocket on the outsole.
